UNITED STATES PATENT OFFICE.

CHARLES W. DORRICOTT, OF PHILADELPHIA, PENNSYLVANIA, ASSIGNOR TO ELECTRELLE COMPANY, OF PHILADELPHIA, PENNSYLVANIA, A CORPORATION OF PENNSYLVANIA.

PNEUMATO-ELECTRIC TRACKER-BAR FOR MUSICAL INSTRUMENTS.

1,088,884.

Specification of Letters Patent.

Patented Mar. 3, 1914.

Application filed June 21, 1912. Serial No. 704,994.

To all whom it may concern:

Be it known that I, CHARLES W. DORRICOTT, a citizen of the United States, residing at Philadelphia, in the State of Pennsylvania, have invented new and useful Improvements in Pneumato-Electric Tracker-Bars for Musical Instruments, of which the following is a specification.

This invention relates to certain new and useful improvements in electro-mechanically controlled playing mechanism for musical instruments, such as pianos, and has to do more especially with an improved construction of pneumato-electric tracker or reader for controlling the operation of the playing mechanism.

Heretofore, and prior to this invention, the usual manner of energizing the electro-mechanically controlled playing mechanism of a musical instrument, was through the medium of an electric tracker or reader comprising a contact bar or roll, and a series of coöperating selector fingers, between which bar or roll and fingers the perforated music sheet is caused to travel, the said bar or roll and the selector fingers being included in circuit with the electro-mechanically controlled playing mechanism. This type of electrical tracker or reader while satisfactory in many respects, is, nevertheless, attendant with more or less serious objections especially where 88 note music is employed, and this has led to the adoption of the type of pneumato-electric tracker such as forms the subject matter of the present application.

Some attempts have heretofore been made to provide pneumato-electric trackers, but so far as I am aware none of these prior devices have gone into practical use for several important reasons, among which may be mentioned the fact that in the prior devices no means were provided for permitting ready adjustment of the numerous electric contacts, which is a matter of great importance in devices of this kind, and furthermore, the prior constructions were not sufficiently compact to meet the present demands of the trade, nor were the pneumatics employed sufficiently sensitive or active to give proper repetition in playing, which is a

matter of prime importance in the present advanced stage of the player-piano.

One of the chief objects of the present invention is to provide a pneumato-electric tracker of normal width capable of use with either 65 or 88 note music and which shall be so simple and compact in construction that it may be associated with the known forms of movable music roll holders without materially altering their construction, the tracker itself containing not only the electric contacts and adjusting means therefor, but also a special construction of pneumatic for actuating the contacts, the tracker as a unit being readily attachable to known forms of music roll holders, such for instance as those constructed to be moved from a position of rest back under the key-bed of a piano to an operative position forward thereof where the music-sheet will be in full view of the performer during playing, this being made possible by reason of the special construction of the tracker and the compact grouping of the parts therein.

A further object of the invention is to provide means for automatically cutting off the air communication with the air-chamber in the tracker when the music sheet rewinding mechanism is thrown into operation, whereby the playing mechanism will not be actuated during the rewinding of the music sheet from the take-up roll back onto the music spool or delivery roll.

A still further purpose of the invention is to provide a simplified construction of circuit wiring between the electric-contacts carried by the tracker and the several electromagnets of the player mechanism, the construction including a cable-conductor and an interposed electric coupling made of separable members so constructed and arranged that the tracker and one member of the said coupling may be assembled as a unit for subsequent attachment to a piano, which latter has attached, at some convenient place thereon, the other member of the said coupling, whereby the labor and expense of applying the whole player mechanism to a piano are greatly simplified and reduced.

In order to enable others skilled in the art

to clearly understand, make and use the invention, I will now describe the same in detail reference being had for this purpose to the accompanying drawings, wherein—

5 Figure 1 is a diagrammatic view or layout of an electro-mechanically operated playing mechanism having associated therewith a pneumato-electric tracker constructed in accordance with the present invention. Fig. 10 10 Fig. 2 is a transverse sectional view of a music-roll holder of the movable type shown associated with the key-bed of a piano. Fig. 15 Fig. 3 is a transverse section taken through the pneumato-electric tracker of the present invention. Fig. 4 is a plan view looking into the tracker from the rear, the rear cover plate of the tracker being removed. Fig. 5 is an elevation of a part of the music roll holder looking in the direction of the arrow, 20 Fig. 2. Fig. 6 is a top plan view, partly in section, of a part of the music roll holder. Fig. 7 is a detail view, partly in section, of a portion of the tracker showing the rewinding mechanism, and the cut-off valve for the 25 air chamber in the tracker. Fig. 8 is an enlarged section of one of the pneumatics and its coöperating contacts. Fig. 9 is a perspective view of a slightly modified way of constructing the pneumatics. Fig. 10 is a transverse sectional view of the electric cable connector.

Referring more particularly to Fig. 1 the reference numeral 1 designates generally the tracker presently to be described in detail, 35 and in which there is an air chamber 5^a maintained under tension by any suitable form of air pump 2 from which a pipe 3 leads to a valve box 4 associated with the music roll holder, presently to be described, 40 and from which valve box a branch pipe 5 leads to the air chamber in the tracker. The pump 2 in the instance shown, is driven from the shaft 6 of an electric motor 7 by the belt 8 carried over a pulley on the shaft 6, and another pulley on the shaft 9 of the 45 pump 2.

The reference numeral 10 designates a music sheet which passes from the delivery roll or music spool 12 over the tracker 1, to 50 the take-up roll 13, said take-up roll being mounted on a shaft 14 carrying a worm gear 15 in mesh with the worm 16 driven by a disk 17, the periphery of which is in frictional contact with a friction disk 18, driven 55 by a belt 19 from the shaft 6 of the electric motor 7, the belt in the present instance being shown as passing over a pulley 20 on the shaft 6. The friction wheel 17, as is usual in constructions of this kind, is so 60 mounted that it may be moved back and forth over the face of the friction disk 18 in order to vary the speed of the take-up roll during the playing of the instrument, in order to change the tempo as desired.

The shaft 14 of the take-up roll has fixed 65 thereto a gear wheel 21 adapted to mesh with a laterally shiftable clutch-pinion 22, and through the medium of sprocket chain gearing 23 the music-sheet may be rewound from the take-up roll 13 back onto the delivery roll 12, the latter being removably mounted in end-bearings carried by the music-roll-holder as usual and well known. The pinion 22 has a clutch associated therewith, and said pinion is shifted into and out 70 of gear with the wheel 21 by means of a clutch-shifter 25, said shifter being actuated by the inclined face 26 of a rotatable block 26^a actuated by a suitable mechanism presently to be described, and said block also has 75 a cam extension 81, adapted to actuate a cut-off valve 27 in the valve box 4 to cut off the air supply or exhaust from the air-tension chamber in the tracker during the rewinding of the music sheet, so that the playing 80 mechanism will not be actuated during such 85 rewind.

The driving mechanism and the rewinding mechanism for the note sheet may be of any preferred construction, the showing here 90 being more or less conventional, and merely by way of illustration. The purpose of the showing is to illustrate the feature of the cut-off valve and the rewinding mechanism, with the means common to both for automatically operating the valve to cut off the communication between the pump and the air chamber in the tracker when the rewinding mechanism is thrown into operation, this being an important feature of the present 95 invention.

In the present instance I have shown my improved form of tracker as associated with a known form of electro-magnetically-controlled hammer-actuating mechanism for the 105 musical instrument, and this mechanism in the instance shown comprises a rotary shaft 28 driven by means of a belt 29 from a pulley on the shaft 6 of the motor 7, the said shaft being constantly rotated at a high speed. 110 Above the shaft 28 and normally out of contact with the periphery thereof, are a plurality of pivoted friction shoes, one to be associated with each unit of the hammer actuating mechanism of the piano, or such 115 thereof as are to be automatically actuated, by any suitable and well known connection. Each friction-shoe is suspended from an armature 31 adapted to be energized by an electro-magnet 32, all the magnets being in 120 circuit with a battery or other suitable source of power 33, and said magnets by means of the wire 33^a and cable 33^b being also in circuit with the several contacts in the pneumato-electric tracker 1 now to be 125 described, the wire 33^a being a common return wire leading from the tracker, and the cable of wires 33^b leading from the several

contact fingers in the tracker, presently to be described, through the magnets 32 to the battery or other source of power.

The tracker or reader of the present invention comprises a face-plate 35, having the usual tracker-ducks 36, and end-walls 37, preferably formed integral with the said face-plate, the latter being shown as provided with longitudinal flanges 38, to which are removably attached the side-walls 39, to which latter is removably attached a rear-wall 40, the said face-plate, end, side and rear walls, forming a hollow box-like structure constituting the air-tension chamber 5^a, maintained under air-tension by means of the pump 2, which has communication therewith by means of the conduit 3, valve-box 4, and pipe 5, as more clearly shown in Fig. 1. This box-like structure is preferably made entirely of metal and the walls are made removable in order that access may be readily had to the interior parts comprising the pneumatics and electric contact members now to be described.

Grouped within the tracker in a convenient and compact manner, as more clearly shown in Fig. 3, are three longitudinally arranged rows or series of pneumatics comprising cups 42, preferably made of metal, each row facing one of the removable walls of the tracker, there being a tube 43, leading from the end of each cup to its appropriate duct-opening 36, in the face-plate 35, of the tracker. The particular manner of grouping the cups provides a very compact arrangement and enables a full complement of 88 pneumatics to be located within a tracker-bar of standard length, width and depth, which is an important factor in devices of this kind especially where they are to be associated with a movable music-roll-holder mounted to be moved back under the key-bed of a piano when not in use, it being understood that the item of knee-room is of material importance.

As all the pneumatics of each row or series and their associated contacts are alike in construction, a description of one will suffice for all and to this end attention is directed more particularly to Figs. 3, 4 and 8, the latter figure showing a single cup-pneumatic and its associated contacts. In this figure the numeral 42, designates one of the cups which is formed with an internal annular shoulder 44, the upper end of the cup being closed by means of a membrane diaphragm 45, which is secured in place by means of a metal ring 46, this construction enabling the parts to be readily assembled without the use of glue. The diaphragm 45, has a button 47, attached to its outer face, the said button and diaphragm being pierced with a small bleed-hole 48, which latter enables the diaphragm to act

very quickly under air impulses and thus it 65 is possible to obtain excellent results in repetition when playing. Arranged within the cup and preferably attached to the inner face of the diaphragm so as to alternately open and close the bleed-opening 48, 70 is a valve 49, the latter serving to prevent said opening from becoming choked or clogged with the fine particles of lint or 75 dust sucked in through the tracker ducts during playing. The valve 49, may be in the form of a flexible flap attached at one end to the inner face of the diaphragm 45, as shown in Fig. 8, or it may be in the form of a disk arranged loosely within the cup, as shown in Fig. 3. Both forms have 80 proven thoroughly practical for the purposes for which they are provided.

Coöperating with the button 47, of each diaphragm is a movable contact finger 50, preferably formed of a narrow strip of 85 thin sheet metal and preferably curved as shown, the free end of which normally rests upon the said button and the opposite end of which is attached to a strip of insulating material 51, extending longitudinally of the 90 tracker, there being two of such strips employed in the construction as shown in Figs. 3 and 4, said strips carrying all the movable contact fingers for all the pneumatics, the alternate fingers of each strip being arranged at right angles to each other, so that some of the fingers will coöperate with one row of pneumatics while the others will co-operate with another row; thus by this arrangement the two strips 51, carry all the 95 fingers for the three rows of pneumatics and space is economized resulting in a compact structure. Arranged alongside each strip 51, is a cable section 52, terminating in the common cable of wires 53, leading to the 100 electric coupling 54, Fig. 1, presently to be described, the wires of the cable sections 52, being soldered or otherwise connected to the contact fingers 50, as more clearly shown in Fig. 3.

Coöperating with the free end of each contact finger 50, is a stationary, but adjustable contact pin 55, a row of said pins passing through and having threaded connection with each of the removable metal walls 115 39 and 40, of the tracker, each pin having an end exposed outside the tracker-bar and provided with a screw-driver notch or other tool-engaging portion whereby it may be readily turned to bring its inner end in 120 proper coöperative adjustment with its associated contact finger 50 without opening the tracker, a lock-nut being threaded on each pin to set the same after adjustment has been made.

In Figs. 3 and 4 I have shown the pneumatics as comprising individual cups 42, but I may form these cups by providing cupped

openings in a solid bar 42^a as illustrated in Fig. 9, it being understood that three such bars will be employed in the structure, the bars being grouped in the same manner 5 in which the cups are grouped as illustrated in Fig. 3.

The electric coupler 54, heretofore referred to, is illustrated in detail in Fig. 10 of the accompanying drawing and comprises in 10 the instance shown a substantially H-shaped base-member 55^a, preferably made of some suitable nonconducting material, secured by screws 56, preferably to the underside of the key-bed of the piano in close proximity to 15 the music-roll-holder and where ready access thereto may be had. The cross-web 57 of the base member carries two rows of yieldable contact members shown as consisting of headed bolts 58, normally urged in 20 one direction by means of the coil springs 59, each bolt carrying a stop-nut 60, to limit its movement in one direction. The said yieldable contact members are each electrically connected to one of the circuit wires 25 33^b leading to the magnets 32, of the electromechanically operated mechanism for the sound-producing devices of the piano, the said wires being arranged in two cables 61, supported by the said base-member 55, of 30 the coupling. Associated with the said base-member 55, is a removable cap-member 62, of insulating material, said cap-member being secured in place by means of screws 63. This cap member 62, carries two rows of 35 metal nuts or disks 64, through the threaded openings of which pass the threaded contact screws 65, the inner ends of said screws making contact with the heads of the yieldable contact members 58. The contact screws 65, 40 are in circuit with the several contact fingers 50, in the tracker, the connection being made by means of the two cable sections 66, carried by the cap member 62, the individual wires of which are connected respectively to 45 the several nuts or disks 64. This construction provides a separable coupling made up of two plate members, one of which is a removable member connected by a cable with the tracker and carrying one set of 50 the two-part contacts of the coupling, hence the tracker with its contacts and the said removable member of the coupling with its contacts, may all be assembled or made up at the factory and afterward easily and 55 quickly attached to a piano. This results in a great saving of time and labor and materially reduces the cost of installation of the attachment in a piano and furthermore enables the tracker and its associated 60 contact coupling member being shipped together as a unit, either as a part of the music roll holder or separate therefrom.

The pump 2 serves to maintain the chamber 5^a in the tracker under constant air-

tension or suction, and whenever any of the 65 perforations in the music sheet 10 register with any of the tracker ducts 36 the diaphragms corresponding to the vented ducts will be drawn outward by means of the air tension in the chamber 5^a and through the 70 buttons 47 move the free ends of the contact fingers 50 into contact with the contact-pins 55, completing the electric circuits to the proper magnets 32 to energize said magnets, which will throw the friction shoes 30 into 75 contact with the revolving shaft 28, and through said shoes and shaft actuate the sound producing mechanism of the piano in the usual way.

As will be seen by referring to Figs. 3 and 80 4 the air tension chamber 41 of the tracker is common to all the pneumatic cups 42 and their associated diaphragms, and this provides a very simple and compact arrangement, enabling the pneumatics to be made 85 comparatively small so that the tracker as a whole need not be any longer, deeper, or wider, than the ordinary form of pneumatic tracker now used and employed in connection with self playing musical instruments 90 of the pneumatic type, and enabling the tracker to be associated with the usual and well-known forms of music roll holders now in use, and which are adapted to be moved to an inoperative position back under the 95 key-bed or forward thereof in front of the keys of the piano as illustrated in Fig. 2 of the accompanying drawings. This compact arrangement of the parts is an important feature of the present invention, and is 100 made possible by reason of the peculiar form and arrangement of pneumatics and contacts employed.

I have shown the improved tracker in connection with a known form of music roll 105 holder that has a combined swinging and sliding movement under the key-base of the piano, and as illustrated more particularly in Fig. 2 of the drawing this music-roll holder comprises in part end-members 70 110 having rearwardly extending arms 71, pivoted at 72 to a plate 73, slidably mounted in guide-ways 74 secured to the under side of the piano key-bed 75. The music roll holder is maintained in playing position by 115 means of a spring latch 76. When out of use the roll holder assumes the dotted line position illustrated in Fig. 2. I do not claim the music roll holder *per se* in this application, as the same will form the subject matter of another application for patent, the showing here being merely by way of illustration to show the improved tracker in association with a bodily movable music-roll holder.

It is important in these tracker-bar constructions that provision be made for adjusting the tracker-bar longitudinally from

time to time, or laterally with reference to the direction of travel of the music-sheet in order that the perforations in the music sheet will at all times accurately register 5 with the tracker ducts, and to accomplish this end I have provided the end members 70 of the roll-holder with open ended boxes 77, having removable cap-pieces as more clearly shown in Figs. 5 and 6, the opposite ends of 10 the tracker being slidably supported in said boxes 77. These boxes serve to support and guide the tracker during adjustment. The tracker is moved longitudinally in either direction by means of a knurled disk 78 carried by a screw 79, which screw has engagement with an end of the tracker and a side member of the music roll holder as more clearly shown in Figs. 5 and 6. Obviously 15 by rotating the screw 79 through the medium of the knurled disk the tracker may be shifted laterally to cause the ducts in the tracker to register accurately with the perforations in the music sheet.

As heretofore pointed out a suitable re-winding mechanism is employed to rewind 25 the music sheet from off the take-up roll back onto the delivery spool, and associated with this mechanism there is a cut-off valve to cut off the air tension supply from the 30 air tension chamber of the tracker, this cut-off valve being employed to prevent actuation of the sound-producing devices when the music sheet is being rewound. This re-winding mechanism and the cut off valve 35 referred to, are more clearly shown in Figs. 1, 2, 6 and 7, wherein the reference numeral 26^a designates a rotatable block adapted to be moved by means of a hand lever 80, said block carrying an inclined face 26, adapted 40 to actuate the clutch shifter 25 for the clutch pinion 22 and the block being further provided with a cam-shaped extension 81, adapted to engage the cut-off valve 27, Fig. 7, so as to cause the same to move inward 45 and cover the port opening 82 leading to the air tension chamber of the tracker, the cut-off valve 27 being normally urged outward by means of a spring 83. It will be apparent from the construction shown that whenever 50 the hand lever 80 is moved so as to cause the inclined face 26 of the block 26^a to shift the clutch pinion 22 to cause the re-winding mechanism to be thrown into operation, the cam extension 81, will, simultaneously with such movement, move the cut-off valve 27 inward, so as to close the port opening 82, in the valve box 4, and thus 55 cut off the air supply or exhaust from the pump 2 to the air tension chamber in the tracker.

What I claim is:—

1. A pneumato-electric tracker comprising a hollow-member having the usual tracker ducts and an air chamber therein, a

plurality of movable contact members 65 mounted within the tracker, pneumatics for actuating said contacts, said pneumatics being located within the tracker and having communication with the tracker ducts, and a plurality of fixed contacts adjustably 70 mounted in an outer wall of the tracker for co-operation with the movable contact members, said fixed contacts, each having a tool engaging portion exposed outside the tracker for the purpose described. 75

2. A pneumato-electric tracker comprising a hollow-member having the usual tracker ducts and an air chamber therein, a plurality of movable contact members mounted within the tracker, pneumatics for actuating said contact members, said pneumatics being located within the tracker and having communication with said ducts, and a plurality of fixed contacts projecting through an outer wall of the tracker, said fixed contacts being adjustably mounted for coaction with the said movable contact members. 80

3. A pneumato-electric tracker comprising a hollow-member having the usual tracker ducts and an air chamber therein, a 90 plurality of movable contact members mounted within the tracker, pneumatics for actuating said contact members, said pneumatics being located within the tracker and having communication with said ducts, a 95 plurality of fixed contact pins projecting through an outer wall of the tracker for coaction with the movable contact members, and means for adjustably supporting the contact pins. 100

4. A pneumato-electric tracker comprising a hollow member constituting an air chamber; said tracker having the usual tracker-ducts and provided with removable side and bottom walls, a plurality of movable contact members located within the tracker, pneumatics for actuating said contacts also located within the tracker and having communication with said ducts, and a plurality of fixed contacts adjustably carried by the removable walls and each having a tool engaging portion projecting outside the tracker, said fixed contacts adapted for coaction with the movable contacts. 105

5. A pneumato-electric tracker comprising a hollow member constituting an air chamber, said tracker having the usual tracker ducts, and provided with removable side and bottom walls, separate rows of diaphragm pneumatics located within the 110 tracker, the diaphragms of each row of pneumatics facing one of the said removable walls of the tracker and said pneumatics communicating with said ducts, a plurality of movable contact springs located within the tracker and each having its free end overhanging one of the said diaphragms, and a plurality of fixed contacts passing 115 120 125

through the said removable walls and each having its inner end mounted for coaction with one of the said movable contacts, said fixed contacts being adjustable toward and from the movable contacts.

6. A pneumato-electric tracker comprising a hollow member having the usual tracker ducts and an air chamber, a plurality of movable contacts mounted within the tracker, diaphragm-pneumatics located within the tracker for actuating said contacts, the diaphragms of said pneumatics each having a vent opening therein and said pneumatics having communication with said ducts and a plurality of fixed contacts adjustably mounted on the tracker for coaction with the movable contacts, said fixed contacts each having a tool engaging portion exposed outside the tracker for the purpose described.

7. A music roll holder comprising a bodily movable frame and means for supporting the same for movement from a position beneath the key-bed of a piano to a position forward thereof, a take-up roll and end bearings for a music spool carried by the roll holder, a pneumato-electric tracker having an air chamber, also carried by the music roll holder, driving means for the take-up roll and rewinding means for one of the end bearings, a valve-controlled conduit leading to the air chamber in the tracker, said conduit and its valve being carried by and movable with the roll holder, and manually operable means also carried by the roll holder for throwing the rewinding mechanism into or out of operation, and for simultaneously opening or closing the valve in the said valve controlled passage.

8. A music roll holder comprising a bodily movable frame, and means for supporting the same for movement from a position beneath the key-bed of a piano to a position forward thereof, a take-up roll and end bearings for a music spool carried by the roll holder, a pneumato-electric tracker having an air chamber also carried by the music roll holder, driving means for the take-up roll, and rewinding means for one of the end bearings, a valve for controlling the air in the tracker, means for throwing the rewinding mechanism into operation and simultaneously operating the cut-off valve, and a manually operable lever common to both said means.

9. A music roll holder having a pneumato-electric tracker removably attached thereto, said tracker comprising a hollow member having the usual tracker ducts and an air chamber, a plurality of pneumatics in said chamber, said pneumatics having communication with said ducts, a plurality of movable contacts in said chamber actuated by said pneumatics, a plurality of fixed contacts

cooperating with the said movable contacts, a cable of circuit wires, each wires of the cable connected to one of said movable contacts, and an electric coupling member having separate terminals to which the opposite ends of said wires are connected. 65

10. A music roll holder having a pneumato-electric tracker removably attached thereto, said tracker comprising a hollow member having the usual tracker ducts and an air chamber, a plurality of pneumatics in 75 said chamber, said pneumatics having communication with said ducts, a plurality of movable contacts in said chamber actuated by said pneumatics, a plurality of fixed contacts coöperating with the said movable 80 contacts, a cable of circuit wires, each wire of the cable connected to one of said movable contacts, and an electric coupling member having separate terminals to which the opposite ends of said wires are connected, 85 said coupling member embodying a plate carrying separate contact elements.

11. A music roll holder having a pneumato-electric tracker removably attached thereto, said tracker comprising a hollow 90 member having the usual tracker ducts and an air chamber, a plurality of pneumatics in said chamber, said pneumatics communicating with said ducts, a plurality of movable contacts in said chamber actuated by 95 said pneumatics, a plurality of fixed contacts coöperating with the said movable contacts, a cable of circuit wires, each wire of the cable connected to one of said movable contacts, and an electric coupling member having 100 separate terminals to which the opposite ends of said wires are connected, said coupling member embodying a plate carrying separate contact elements, said contact elements being adjustably mounted in the 105 plate.

12. A music roll holder having a pneumato-electric tracker removably attached thereto, said tracker comprising a hollow member having the usual tracker ducts and an air chamber, a plurality of pneumatics in 110 said chamber, said pneumatics communicating with said ducts, a plurality of movable contacts in said chamber actuated by said pneumatics, a plurality of fixed contacts 115 coöperating with the said movable contacts, a cable of circuit wires, each wire of the cable connected to one of said movable contacts, and an electric coupling member having separate terminals to which the opposite 120 ends of said wires are connected, said coupling member comprising a strip of insulating material, and a plurality of contact pins adjustably mounted in said plate, said pins being electrically connected to the 125 wires of the cable.

13. In combination with electrically operated playing mechanism for a musical in-

strument embodying a plurality of electro-magnets and an electric coupling member including electric terminals, one for each of said magnets, a pneumato-electric tracker
5 having the usual tracker ducts and an air chamber, a plurality of pneumatically actuated contact members within the tracker, a plurality of coöperating contacts carried by the tracker, a cable of wires leading from
10 the said movable contacts, said cable of wires terminating in an electric coupling member

having terminals, said last named coupling member being adapted to be coöperatively associated with the first named coupling member.

15

In testimony whereof I have hereunto set my hand in presence of two subscribing witnesses.

CHARLES W. DORRICOTT.
